(57) **CLAIM**

The ornamental design for a headset, as shown and described.

DESCRIPTION

FIGS. 1-9 illustrate a headset in which

FIG. 1 is a front perspective view thereof;

FIG. 2 is a front elevation thereof;

FIG. 3 is a rear elevation view thereof;

FIG. 4 is a right elevation view thereof;

FIG. 5 is a left elevation view thereof;

FIG. 6 is a top plan view thereof;

FIG. 7 is a bottom plan view thereof;

FIG. 8 is a rear perspective view thereof; and,

FIG. 9 is a front perspective view thereof showing in dotted line an exemplary module that can be attached to the headset.

The broken lines in the figures are for the purpose of illustrating environmental structure and form no part of the claimed design.

1 Claim, 9 Drawing Sheets
